UNITED STATES PATENT OFFICE.

WALTER F. KEENAN, JR., OF PELHAM, NEW YORK, ASSIGNOR TO FOSTER WHEELER CORPORATION, OF NEW YORK, N. Y., A CORPORATION OF NEW YORK.

SUPERHEATER BOILER.

Application filed October 29, 1924. Serial No. 746,541.

The general object of the invention is to provide an improved superheater boiler construction. More specifically, the object of the invention is to combine superheating provisions with a known type of marine type boiler to provide an efficient superheater boiler of simple and reliable construction and characterized by its relatively small bulk and weight per unit of capacity, its relatively low draft losses and the manner in which the superheater provisions are incorporated in and made part of the combustion chamber wall of the boiler furnace.

The various features of novelty which characterize my invention are pointed out with particularity in the claims annexed to and forming a part of this specification; but for a better understanding of the invention, its advantages and specific objects attained with it, reference should be had to the accompanying drawings and descriptive matter in which I have illustrated and described a preferred embodiment of the invention.

25 Of the drawings:

Fig. 1 is an elevation in section, the section being taken on the line 1—1 of Fig. 3;

Fig. 2 is a partial section on the line 2—2 of Fig. 1; and

Fig. 3 is a partial elevation of the boiler.

The boiler shown in the drawing comprises two parallel water drums B located at the same level at the opposite sides of the combustion chamber A of the boiler furnace.

35 At an upper level, and midway between and parallel to the water drums B is a steam and water drum C. Each water drum B is connected to the steam and water drum C by a corresponding bank of inclined tubes D.

40 To simplify the illustration only the tubes D at the opposite sides of each bank are shown in Fig. 1. The heating gases after passing through the banks of water tubes D, which may be baffled in any usual manner, pass 45 into heating gas outlet spaces A' in the boiler housing from which they are discharged by stack connections not illustrated. In so far as above described, the boiler illustrated contains nothing novel with me, but on the contrary is of a type well known and in extensive use particularly for marine purposes.

In accordance with the present invention, each side wall of the combustion chamber 50 beneath the corresponding water drum B

incorporates, and as shown in effect is formed by a radiant heat superheater. Each superheater is composed of superheating elements E, and the supports and heat insulation for the elements. Each element 60 E is formed of two cast steel sections connected end to end at E'. The elements E of each superheater are generally rectangular in section and are arranged one above another to form a smooth wall at the corresponding side of the combustion chamber. Each element E is connected at one end by an outwardly extending flexible tube E² to a vertical inlet header F, and at its other end is connected by a similar tube E² to a vertical outlet header F'. Each superheater element section is rigidly connected adjacent the joint E' to a portion of the superheater supporting frame work shown as a corresponding vertical channel bar G at the outer 75 side of the elements. The connecting provisions include a lug E³ welded or otherwise rigidly secured to the element section. Adjacent its free end each section of the element is connected to another portion of the 80 superheater supporting frame work in the form of another vertical channel bar G, the connection including a corresponding lug E⁴ welded or otherwise rigidly connected to the section.

85 In addition to the four channel bars G, the supporting frame work for each superheater also comprises a vertical metal plate H, top and bottom channel bars I, and vertical channel bars K at the ends of the superheater secured between the plate H and an outer metal plate J, the parts of the frame work being suitably connected as by rivets or welding. A closed heat insulating space 90 is thus provided between the plate J and the plate H. The inlet and outlet headers F and F' of each superheater are secured by clamping yokes F² to bracket J' secured to the plate J. Suitable heat insulating material L as Sil-o-cel is packed in the space 95 between the elements E and the plate H. As shown, the lower element E of each superheater is spaced above the bottom of the combustion chamber on ledge portions N' of the fire brick floor N of the combustion chamber. Advantageously, the fire brick floor N is mounted on a layer of heat insulating material O which may well consist of Sil-o-cel. Above the uppermost element E in each superheater there are advanced 100

stageously placed one or two tiers of fire brick P, and the heat insulation L between the superheater is advantageously extended into contact with the under side of the water drums B and between the latter and the subjacent channel bars I. In practice the connections between the superheater element lugs E⁴ and the corresponding supports G are slotted to accommodate the thermal 10 elongation and contraction of the elements which are anchored through the connecting lugs E³ to the central supports G. For the same reason the holes in the plates H and J through which the tubes E² extend 15 are advantageously elongated in a horizontal direction, but these features of construction did not originate with me and form no part of the invention claimed herein.

The boiler proper may be supported in 20 any usual or suitable manner and its weight and that of the upper portion A² of the boiler housing may be carried in whole or in part on the supporting frame work of the superheaters but preferably is sustained in 25 whole or in large part by the end walls A³ of the boiler housing or by pedestals M at the ends of the latter. The boiler furnace shown was designed for oil firing but the use of the invention is obviously not dependent 30 on the character of the combustion provisions (not shown) which may be employed in or in connection with the combustion chamber of the boiler.

It will be apparent that the elements and 35 supporting frame work of each superheater form a separate and distinct portion of the combustion chamber wall and replace heavy refractory wall portions of masonry which would otherwise have to be employed, so 40 that the addition of the superheater to the otherwise old boiler in the manner described need not add to the bulk or weight of the boiler. Furthermore, the superheaters are advantageously located to secure a given 45 superheating effect with a relatively small amount of superheating surface and without in any wise impeding the draft through the boiler. The location of the superheaters at the bottom of the boiler rather than at a 50 higher level is especially desirable in the case of a marine boiler because of the resultant lowering in the height of the center gravity of the boiler. The use of radiant heat superheaters in the walls of the combustion chamber of a compact boiler intended for operation at high ratings like the marine type of boiler illustrated, is especially desirable because they permit the use 55 of energetic and highly efficient combustion conditions without injurious effect on the combustion chamber walls. The superheaters are not only themselves practically immune from injury by overheating, but they cool and thereby protect the end walls A³ 60

against overheating by absorbing radiant 65 heat from the latter.

While in accordance with the provisions of the statutes I have illustrated and described the best form of my invention now known to me, it will be apparent to those skilled in the art that changes in the form of apparatus specifically illustrated and described herein may be made without departing from the spirit of my invention as set forth in the appended claims, and that certain features of my invention may sometimes be employed with advantage without a corresponding use of other features.

Having now described my invention what I claim as new and desire to secure by Letters Patent is:

1. The combination with a boiler comprising parallel water drums at the sides of the furnace combustion chamber and water tubes connecting said drums to an upper 85 steam and water drum, of means for superheating the steam generated in the boiler at approximately boiler pressure consisting of a radiant heat superheater located beneath each water drum and forming a corresponding portion of the wall of the combustion chamber.

2. In a boiler furnace of the type comprising a horizontal water drum at one side of the furnace combustion chamber and upwardly extending water tubes connected to the drum, the improved means for heating steam generated in the boiler at approximately boiler pressure which consists in a radiant heat superheater located beneath said drum and comprising horizontally disposed elements uniting to form a heat absorbing combustion chamber side wall and a structural support for said elements at the outer sides of the latter.

3. In a boiler furnace of the type comprising a horizontal water drum at one side of the furnace combustion chamber and upwardly extending water tubes connected to the drum, the improved means for heating steam generated in the boiler at approximately boiler pressure which consists in a radiant heat superheater located beneath said drum and comprising horizontally disposed elements uniting to form a smooth surface absorbing heat from the combustion chamber, a structural support for said elements at the outer sides of the latter, and heat insulating material supported by said frame work between it and the elements and uniting with said frame work and elements to form a unit section of the combustion chamber wall.

Signed at New York city, in the county of New York and State of New York, this 27th day of October, A. D. 1924.

WALTER F. KEENAN, JR.
